CORDLESS TAPE WINDER

Donald A. Burns, Putnam Valley, N.Y., assignor to
Donald A. Burns

Filed Feb. 13, 1975, Ser. No. 549,710

Term of patent 14 years

Int. Cl. D14—99; D16—05

U.S. Cl. D26—14 B

FIG. 1

FIG. 5

FIG. 4

FIG. 2

FIG. 3

FIG. 1 is a front elevation of a cordless tape winder showing my new design;

FIG. 2 is a top plan view;

FIG. 3 is a side elevation;

FIG. 4 is a front perspective view; and

FIG. 5 is a rear elevation thereof.

The broken lines showing wound tape in FIG. 4 are for illustrative purposes only.

I claim:

The ornamental design for a cordless tape winder, as shown and described.
